CLAIM

The ornamental design for a dual nozzle applicator for the delivery of solutions and materials in a pressurized fluid system, as shown and described.

DESCRIPTION

FIG. 1 is a front view of the dual nozzle applicator for the delivery of solutions and materials in a pressurized fluid system showing new design;

FIG. 2 is a top view thereof;

FIG. 3 is a right side view thereof;

FIG. 4 rear view thereof;

FIG. 5 is a left side view thereof; and,

FIG. 6 is a bottom view thereof.
